(57) **CLAIM**

The ornamental design for an electronics device mount, as shown and described.

DESCRIPTION

FIG. 1 is a top, front, right isometric view of an electronics device mount incorporating our new design;

FIG. 2 is a front end elevation view thereof;

FIG. 3 is a rear end elevation view thereof;

FIG. 4 is a right-side elevation view thereof;

FIG. 5 is a left-side elevation view thereof;

FIG. 6 is a top plan view thereof; and,

FIG. 7 is a bottom plan view thereof.

The dashed broken lines in the drawings show unclaimed features of the design, and the dashed-dot broken lines represent boundaries of the design. All of the broken lines form no part of the claimed design.
